(57) **CLAIM**

The ornamental design for a television receiver, as shown and described.

DESCRIPTION

FIG. 1 is a perspective view of a television receiver showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and

FIG. 7 is a bottom plan view thereof.

FIG. 8 is a reference front elevational view thereof, showing where enlarged reference views 9, 10 and 11 are taken from;

FIG. 9 is a reference enlarged view of a portion 9 of FIG. 8;

FIG. 10 is a reference enlarged view of a portion 10 of FIG. 8; and,

FIG. 11 is a reference enlarged view of a portion 11 of FIG. 8.

The broken lines shown in FIGS. 3 and 6 define the bounds of the claimed design.
